UNITED STATES PATENT OFFICE.

CARL HAMBUECHEN, OF BELLEVILLE, ILLINOIS, ASSIGNOR, BY MESNE ASSIGNMENTS,
TO NATIONAL CARBON COMPANY, INC., OF CLEVELAND, OHIO, A CORPORATION OF
NEW YORK.

BATTERY HAND-LAMP.

1,289,459.

Specification of Letters Patent. Patented Dec. 31, 1918.

Application filed October 18, 1917. Serial No. 197,198.

To all whom it may concern:

Be it known that I, CARL HAMBUECHEN, a citizen of the United States, residing at Belleville, in the county of St. Clair, State 5 of Illinois, have invented certain new and useful Improvements in Battery Hand-Lamps; and I do hereby declare the following to be a full, clear, and exact description of the invention, such as will enable 10 others skilled in the art to which it appertains to make and use the same.

The present invention relates to improvements in hand lamps of the general type in which there is a casing of insulating material provided at one end with a lamp and reflector and within which a dry battery is held by means of a cap screwed on the other end of the casing. The lamp circuit is controlled by a switch usually placed on the 20 side of the casing, and the cap is so constructed that it may be manipulated to cause a second break in the circuit when desired, the object of the second break being to prevent inadvertent lighting of the lamp if the 25 switch is accidentally operated when the lamp is being carried about as for instance in the pocket. It is an object of the present invention to improve the construction of hand lamps of this general character and 30 particularly to arrange the parts so that a push button type of switch may be used for controlling the lamp circuit. A further object is to make the bottom cap of a construction which is simple and yet effective 35 for opening the lamp circuit when the cap is partially unscrewed.

In accordance with the present invention an insulating casing is provided having attached to its inner surface two fixed contact 40 strips, one of which makes electrical connection with a reflector within which a lamp is mounted at the front end of the casing, while the other strip extends to the other or rear end of the casing. The circuit between these two contact strips is controlled 45 by a switch of the push button type, preferably provided with an auxiliary switch of the sliding contact type whereby the lamp circuit may be left in closed condition inde- 50 pendently of the push button switch. The cap which screws onto the rear end of the casing has a spring to retain the battery in place against the lamp terminal and the cap is provided with means for contacting with 55 the rear end of the second contact strip when

the cap is screwed substantially to its limit of movement. If however the cap is unscrewed a certain distance this contact is broken so that the lamp circuit cannot be completed even if the switch should be inadvertently closed. 60

The particular nature of the invention as well as other objects and advantages thereof will appear most clearly from a description of certain preferred embodiments as shown 65 in the accompanying drawings in which Figure 1 is a sectional elevation through the complete hand lamp. Fig. 2 is a plan view of the complete device; Fig. 3 is a section through a portion of the casing and the 70 rear cap on the line 3—3 of Fig. 1; Fig. 4 is a similar section along the line 4—4 at the front of the device; Fig. 5 is an end elevation showing the inside of the cap; Fig. 6 is a detail view showing the switch 75 plate removed from the cap; Fig. 7 is a sectional elevation of a lamp provided with a cap of modified construction and Fig. 8 is a section through the end of this lamp along the line 8—8 of Fig. 7. 80

Referring to the drawings in which similar reference characters denote similar parts throughout the several views, 10 represents a tubular casing preferably constructed of insulating material such as hard fiber. Surrounding the forward end of the casing is a metallic sleeve 11 which is screw threaded to receive a collar 12 for holding in place the lens 13 and also for clamping between the lens and the end of the casing a reflector 14 which has at its inner end a socket 15 within which a small incandescent bulb 16 is screwed. One terminal of the lamp constitutes the usual screw threaded plug portion while the other terminal 17 90 is adapted to be engaged by the terminal 18 of a battery 19 preferably composed of a plurality of dry cells arranged end to end and mounted in a removable carton within the casing. A contact strip 20 is attached 95 to the inside of the casing as by rivets 21 and at its forward end this strip is bent to engage the outer surface of the reflector 14. The rivet at the forward end of the contact strip should preferably be concealed beneath 100 the sleeve 11 and in order to prevent electrical contact with this sleeve a piece of insulating material 22 may be provided.

A second contact strip 23 is attached to the inside of the casing by a rivet 24 near 110

its rear end, but at its forward end it is connected, by means of a rivet passing through the casing, to one of the curved wing portions of a shield 25 containing the switch mechanism. Upon the top of the shield 25 is a sliding member or thumb piece 26 which has tangs 27 adapted to pass through longitudinal slots in the shield. The ends of these tangs are clenched under a resilient metal contact element 28 and fit within recesses in the edge of this element to provide for moving the same by motion of the thumb piece. The contact element has a downwardly extending end portion 29 adapted to engage an enlarged head on the outer end of the rivet 21 which holds the contact strip 20 in place. A second contact element 30 is held in place between the first contact element 28 and the top of the shield. This second contact element is of resilient metal and is provided with recesses on its edges through which the tangs 27 of the thumb piece extend. The recesses on contact element 30 are somewhat longer than those on the contact element 28 in order to permit motion of the latter in respect to the shield. The free end of contact element 30 has attached to it a push button 31 which, when the contact element is in its normal position extends through an opening in the top of the shield. A contact point 32 may be applied to the underside of contact element 30 in a position to engage the enlarged head of the rivet at the inner end of the contact strip 20.

When the members of the switch occupy the position shown in the drawings the lamp circuit will be open as both of the contact elements are out of engagement with the head of stud or rivet 21 forming one terminal of the battery circuit. When it is desired to light the lamp and retain control of the latter under the thumb or fingers of the user, the push button 31 is depressed bringing contact point 32 into engagement with the head of rivet 21 thus bridging the gap between the ends of the conducting strips 20 and 23. As long as the button is held depressed the lamp circuit will be closed, but as soon as it is released the contact element will spring back to its normal position thus opening the lamp circuit. If it is desired that the lamp shall burn continually without the necessity of holding the push button depressed, thumb piece 26 is slid along the shield and carries with it contact element 28 bringing the end 29 in engagement with the head of rivet 21. The other contact element 30 does not, however, partake of the sliding motion of the first contact element since the button extending through the top of the shield prevents any considerable longitudinal movement. In order to break the circuit the thumb piece must be restored to normal position.

At the rear of the casing is a sleeve 35

similar to the sleeve 11 at the front of the casing. The head of rivet 24 should preferably be concealed under sleeve 35 and insulated from the latter by a piece of appropriate insulating material 36. A cap 37 is provided with a screw threaded portion 38 adapted to fit on the sleeve 35. Within the cap is mounted switch mechanism adapted to engage the rear end of the contact strip 23 when the cap is screwed completely on to 75 the sleeve. Figs. 1, 5 and 6 show one construction that may be used. It comprises a substantially circular switch plate 39 provided at its edge with a number of ears 40 which when the plate is forced into place 80 in the cap, spring into a circular groove formed between the end of the cap and the screw threaded portion 38 thus holding the switch plate normally within the cap. The switch plate is provided with an annular 85 ridge 41 having curved sides, the outer one of which is adapted to engage the bent rear end of the contact strip 23 as shown most clearly in Fig. 1. The switch plate is also provided with a second ridge or groove 42 90 having an opened portion to permit one end of a coil spring 43 to enter beneath the ridge and thereby be detachably secured to the switch plate. The coil spring is preferably of tapering form, the smaller end being adapted 95 to engage the rear end of the battery. In batteries of this construction this rear end forms one terminal and the metallic electrode of the battery is left exposed so that the circuit may be completed through the 100 spring and the inclosing cap.

With the arrangement described above, the circuit to the contact strip 23 cannot be completed from the terminal of the battery unless the cap 37 is screwed completely on 105 to the sleeve 35, or at least so far that the ridge 41 comes into contact with the end of the strip 23. When this occurs the spring 43 will be under sufficient compression to hold the battery firmly against the inner 110 terminal of the lamp, so that the lamp circuit may be finally completed by manipulation of the switch mounted on the side of the casing. When the lamp is to be carried in the pocket, the cap may be unscrewed 115 sufficiently to bring the ridge 41 out of contact with the end of the strip 23 in which case there will be a break in the circuit at this point so that even if the switch is accidentally manipulated there will be no chance 120 for the lamp circuit to be established. Whether the cap be unscrewed or not any piece of metal, as for instance a metal tool, which may come in contact with the collar 12 and the cap 37 at the same time, will not 125 establish the lamp circuit for the forward end of the contact strip 20 engages the reflector only and there is no chance for the current to reach the reflector from the collar 12 since the sleeve 11 upon which the 130

collar is screwed is set back a slight distance from the outer edge of the fiber casing, thus insulating these metallic fittings from the reflector.

- 5 The modification shown in Figs. 7 and 8 is of somewhat simpler construction and comprises a tapering coil spring 45 set into the groove formed in the outer edge of the cap so that it is retained in place. This 10 spring is so formed that when the cap is screwed completely onto the end of the casing one of the convolutions of the spring will come into engagement with the end of the contact strip 23 to establish the circuit 15 through the contact strip. By unscrewing the cap a certain amount, the contact is broken so that the lamp will not be accidentally lighted.

It will be understood that while two modifications of the invention have been shown, it is capable of being embodied in other constructions.

I claim—

1. In a battery hand lamp, the combination of a tubular casing, a battery therein, 25 a metallic reflector at one end of the casing, a lamp mounted in the reflector with one terminal electrically connected thereto, and the other terminal connected to one terminal 30 of the battery, a lens associated with the reflector, metallic fittings insulated from said reflector for holding said lens in place, circuit connections between the other terminal of the battery and said reflector, said connections including two conductors fixed in 35 position upon the inside of the casing and two switch mechanisms arranged in series, one of said switch mechanisms being adapted to establish a circuit between the said 40 conductors, and the other mechanism including a conducting cap for holding the battery in place and included in the circuit through one of said conductors.

2. In a battery hand lamp, the combination 45 of a tubular casing, a battery therein, a metallic reflector at one end of the casing, a lamp mounted in the reflector with one terminal electrically connected thereto, and the other terminal connected to one terminal 50 of the battery, a lens associated with the reflector, metallic fittings insulated from said reflector for holding said lens in place, circuit connections between the other terminal of the battery and said reflector, said 55 connections including two conductors fixed in position upon the inside of the casing and two switch mechanisms arranged in series, one of said switch mechanisms being adapted to establish a circuit between the said 60 conductors and the other mechanism including an all metallic cap detachably mounted on the other end of the casing, and means within said cap and electrically connected thereto and to the other terminal of the battery for establishing a circuit from this ter-

minal of the battery to said second conductor.

3. In a battery hand lamp, the combination of a tubular casing, a battery therein, a metallic reflector at one end of the casing, 70 a lamp mounted in the reflector with one terminal electrically connected thereto and the other terminal connected to one terminal of the battery, a lens associated with the reflector, metallic fittings insulated from said reflector for holding said lens in place, a metallic cap detachably mounted on the other end of the casing, a conductor fixed on the inside of the casing and having electrical connection with said reflector, a second 75 conductor mounted in fixed position on the inside of the casing, a switch mounted on the casing for completing the circuit between the said conductors, a metallic switch plate within and having electrical contact with 80 the cap and adapted to engage said second conductor when the cap is in place, and means within said cap for electrically connecting the other terminal of the battery to the plate. 90

4. In a battery hand lamp, the combination of a casing, a battery therein, a lamp mounted in one end of the casing and having one terminal connected to one terminal of the battery, a metallic cap detachably 95 mounted on the other end of the casing, a conducting member mounted within the cap and held in place by a groove on the edge of the cap, means connected to said member and adapted to form an electrical connection 100 with the other terminal of the battery when the cap is in position, a conductor fixed within the casing and adapted to be engaged by said conducting member when the cap is in position and a switch mounted on the casing 105 adapted to establish a circuit between the conductor and the lamp.

5. In a battery hand lamp, the combination of a cylindrical casing, a battery therein, a lamp mounted in one end of the casing 110 and having one terminal connected to one terminal of the battery, a cap detachably mounted on the other end of the casing, a circular conducting member within the cap, and provided on its edge with ears fitting 115 into a groove in the outer edge of the cap, means connected to said member and adapted to form an electrical connection with the other terminal of the battery when the cap is in position, a conductor fixed within the 120 casing and adapted to be engaged by said conducting member when the cap is in position and a switch mounted on the casing adapted to establish circuit between the conductor and the lamp. 125

6. In a battery hand lamp, the combination of a tubular casing, a battery therein, a metallic reflector at one end of the casing, a lamp mounted in the reflector with one terminal electrically connected thereto and the 130

other terminal connected to one terminal of the battery, a lens associated with the reflector, metallic fittings insulated from said reflector for holding said lens in place, a 5 metallic cap detachably mounted on the other end of the casing, a conducting plate in electrical contact with the inside of said cap and provided with a groove, a coiled spring having one end retained in the groove 10 and adapted to engage the other terminal of the battery, a conductor fixed within the casing and adapted to be engaged by said conducting plate when the cap is in position and a switch on the side of the casing for 15 establishing circuit between said conductor and the reflector.

7. In a battery hand lamp, the combination of a casing, a battery therein, a lamp mounted in one end of the casing and having 20 a terminal engaging one terminal of the battery, a metallic cap detachably mounted on the other end of the casing, a conducting plate in electrical contact with the inside of the cap, said plate being provided with a 25 substantially circular open-ended groove and a circular ridge, a coiled spring having one end retained in the groove and adapted to engage the other terminal of the battery, a conductor fixed within the casing and having 30 a free end adapted to be engaged and forced outwardly by the ridge on the plate when the cap is in position, and a switch on the casing for establishing circuit between said conductor and the lamp.

35 8. In a battery hand lamp, the combination of a tubular casing, a battery therein, a lamp mounted in one end of the casing and having one terminal connected to one terminal of the battery, a metallic cap detachably

mounted on the other end of the casing, a 40 circular conducting plate arranged in electrical contact with the inside of the cap, said conducting plate being provided with an annular open-ended groove and a closed annular ridge having sloping sides, a tapering 45 coiled spring having its larger end retained in the groove and its smaller end engaging the other terminal of the battery, a conductor fixed within the casing and having an inwardly bent rear end adapted to be 50 engaged and forced outwardly by one side of the annular ridge when the cap is in place, and a switch on the casing adapted to establish circuit between the conductor and the lamp. 55

9. In a battery hand lamp, the combination of a tubular casing, a battery therein, a metallic reflector at one end of the casing, a lamp mounted in the reflector with one terminal electrically connected thereto and the 60 other terminal connected to one terminal of the battery, a lens associated with the reflector, metallic fittings insulated from said reflector for holding said lens in place, a cap 65 detachably mounted on the other end of the casing, a conducting member fixed in position within the casing, a coiled spring retained within said cap and engaging the other terminal of the battery, said spring being grounded on said cap and adapted to 70 be brought into or taken out of electrical connection with said conducting member by movement of the cap on the end of the casing, and a switch on the side of the casing for 75 establishing circuit between said conducting member and the reflector.

In testimony whereof I affix my signature.
CARL HAMBUECHEN.
